UNITED STATES PATENT OFFICE.

JOHN BOSTON, OF NEWARK, NEW JERSEY, ASSIGNOR, BY MESNE ASSIGNMENTS, TO THOMAS CARTER & SONS, INC., A CORPORATION OF NEW YORK.

STRIP-GUIDE FOR SEWING-MACHINES.

1,391,876.

Specification of Letters Patent. Patented Sept. 27, 1921.

Application filed September 4, 1918. Serial No. 252,526.

To all whom it may concern:

Be it known that I, JOHN BOSTON, a citizen of the United States, and a resident of Newark, in the county of Essex and State 5 of New Jersey, have invented certain new and useful Improvements in Strip-Guides for Sewing-Machines, of which the following is a specification.

My invention relates to a gate for sewing 10 machines and while I have applied the same to a hemstitching machine I desire it to be understood that the invention is suitable for all forms of sewing machines. In sewing machines, where the fabric in very long 15 strips is fed from a pile or from a roller, as where handkerchief material is hemstitched in large quantities, it is customary to provide a guiding device to guide the fabric as it feeds from the supply into the stitching 20 mechanism and folder or hemmer. These devices are usually called gates and they have generally consisted of a structure immovably attached to the sewing machine or to some part of the bench. These gates 25 usually project beyond and above the edge of the bench on which the sewing machine is mounted, and they more or less obstruct the sewing machine so that the operator has to lean over the gate and reach out to thread 30 the needle and to attend to other parts of the sewing machine. The object of my invention is to provide a very simple and convenient gate which will swing or fold up close to the machine if the operator presses 35 against it, so that she may approach the machine as closely as if the gate were not present. This gives the operator perfect freedom so that she can more conveniently thread the needle or attend to any part of the machine. At the same time, the gate is not 40 rendered inoperative when it is moved inwardly nor is the fabric displaced thereon; and when the operator moves away from the gate the latter automatically swings back 45 into position.

In the drawings forming part of this application,

Figure 1 is a plan view of part of the sewing machine and the gate,
50 Fig. 2 is a front elevation thereof,

Fig. 3 is a sectional view through the sewing machine bench and showing the gate in end elevation,

Fig. 4 is a sectional view, taken on the line 3-3 of Fig. 5, and

Fig. 5 is an enlarged plan view of one end 55 of the gate.

I have shown only such parts of the sewing machine as are necessary to indicate the disposition of the gate and its function of 60 guiding the fabric. In the drawings I have shown a bench 1 on which one or more sewing machines may be mounted. At 2 I have shown the presser foot of the sewing or hemstitching machine and at 3 is the needle shaft 65 which carries the sewing needle 4. The curved plate 5 constitutes a well known form of folder for turning the edge of the fabric so that the folded edge will be stitched by 70 the machine to form a hem, either hemstitched or otherwise, along one side edge of the fabric.

The gate or guide which is the subject matter of the present invention, is preferably attached to the bench or machine support 75 1 so that it lies at the front thereof.

At 6 I have shown a pair of arms 7 pivoted to the brackets 8 and spaced apart lengthwise of the bench a distance somewhat greater than the width of the widest 80 fabric which is to be fed into the sewing machine. These arms, at their outer ends, are pivoted to the lower ends of the upwardly extending supports 9, whereby the arms 7 form a portion of the supporting 85 means for the supports 9. The arms 10, pivoted to the brackets 8 at 11 extend outwardly from the bench above the arms 7 and at their outer ends they are connected to the supports 9 by means of a bar or rod 12 on 90 the latter, which slides in slots 13 in the arms 10.

At their upper ends, the supports 9 are connected by a cross bar or rod 14 and below by another bar 15, so that the supports 95 9 and these connecting bars move as a whole and are in the nature of a frame. At the ends of the gate there are adjustable arms 16 which are pivoted to the lower arms 7 between the ends of the latter, by 100

means of bolts 17 which pass through holes in the arms 7 and through slots 18 in the arms 16 so that the pivotal points between the arms 7, and the arms 16 may be adjusted. At their upper ends the arms 16 are pivoted to the rod 12.

On the upper cross rod 14 there are collars 19 which may be secured at any desired position along the rod by the screws 20 and 10 these collars each have a flange 21 for engaging an edge of the fabric to guide it or to prevent the fabric from shifting laterally along the rod 14 while passing over it. In 15 like manner, the collars 22 are adjustably secured on a lower cross bar or rod 26, by the screws 23 and these collars have similar guiding flanges 24 adapted to prevent lateral shifting of the fabric where it travels over the rod 26. There is a bracket 25 secured 20 on each arm 7 near each support 9 and they are connected by a cross bar 27 lying close to and parallel with the cross bar 26.

In addition to the above parts I have provided 25 guides near the folder which do not move with the gate, so that these guides remain in the same position relatively to the folder plate 5 while the gate is moving. The guide 28 is nearest the bench 1 and it is adjustably held on brackets 29 by thumb screws 30. The arm 31 reaches over the left edge of the fabric in Figs. 1 and 2 so that it guides this edge of the fabric substantially on the line of the bench top 1 and it 35 prevents the fabric from shifting to the left. There is a bracket 32 at the right side of the fabric and on this there is secured an arm 33 which reaches over the right edge of the fabric to guide it in relation to the 40 folder plate.

Operation: In threading the fabric over the gate and into the machine, the free end is brought up from the pile or bolt of cloth (not shown), which is generally placed 45 below the gate, and the end is passed over the bar 27 and then under the bar 26, thence in front of the bars 15 and 12 and over the bar 14. From there it is passed under the guides 33, 31 and thence over the 50 bench 1, the right hand edge being inserted into the folder plate 5. It will be understood that the flanges 21 and 24 will be adjusted on the rods 14, 26, to engage the side edges of the fabric and guide the fabric 55 in proper relation to the folder 5. If a wide hem is to be turned, naturally, the flanges will be placed more to the right, whereas, if a narrow hem is to be turned, they will be placed more to the left. They 60 will be spaced apart, also, according to the width of the fabric.

The fabric will feed over and through the various guiding elements above referred to, passing from the source of supply and 65 through the folder 5, at which latter place

the fabric is stitched, and the forward end of the fabric will either be allowed to drop into a pile or it will be taken up by any suitable reeling device.

In the ordinary operation of the gate it 70 will stand in the position shown in the drawings, so that the fabric will be guided about the same as with a stationary gate. But if the operator approaches closely to the machine she may press against the front 75 of the gate and this will cause the latter to swing or fold up toward the bench. Pressure against the supports 9 or any of the cross bars carried by them, will cause the supporting arms 7, 10 to swing upwardly 80 and toward the bench 1 and the supports 9 will rise slightly and approach the bench, the rod 12 sliding in the slots 13, thus allowing the operator to approach about as near to the bench as would be possible if the gate 85 were not present. As hereinbefore set forth, the operator is thus better able to approach closely to the machine to thread the needle and to otherwise attend to the operation of the machine. When the gate 90 thus folds or swings toward the bench, the fabric is not displaced. When the operator withdraws from the gate the latter swings back automatically, by gravity, to the position shown in the drawings. 95

It is desirable to adjust the height of the gate in relation to the folder 5 in order to feed the fabric properly when a wide hem is being turned or when a narrow hem is being turned. The adjustment of the gate 100 may be made by loosening the bolts 17 which secure the arms 7 and 16 together and then the gate is swung upwardly on its pivots 6, 11 until the top bar 14 is at the desired height. During this adjustment the bolts 17 105 travel in the slots 18 of the arms 16. When the desired adjustment has been obtained, the bolts 17 are tightened, and this fixes the point of connection of the arms 7 and 16 again. With the new adjustment made, the 110 gate will operate as before, but when it swings out or away from the bench it will stop at a different position, i. e., it will come to rest with the bar 14 at a higher level than before the adjustment was made. The ad- 115 justment may be made to lower the bar 14 at any time, so that the fabric will leave the gate at the elevation necessary to obtain the proper angle of feeding for different folders.

It will be observed that when the gate 120 swings toward or from the bench that the bar 14, from which the fabric finally leaves the gate, does not change its distance from the guide 33 sufficiently to interfere with the feeding of the fabric. Thus, there is no 125 great slack in the fabric between the bar 14 and guide 33 as the gate folds or opens, so that there is no tendency to interfere with the feeding of the fabric. By making the gate adjustable in height as well as foldable 130

or collapsible I am able to obtain all the desired advantages in a folding or movable gate.

Having described my invention, what I claim is:

1. The combination with a sewing machine and its support, of a gate for guiding the fabric to the stitching mechanism of the sewing machine, said gate comprising 10 hinged supports projecting forwardly from the sewing machine, fabric guiding means carried by said hinged supports, said supports being adapted to be swung inwardly toward the sewing machine by pressure of 15 the operator's body against the front of the gate to permit the operator to approach close to the sewing machine and adapted to swing outwardly to normal position when pressure of the body thereon is released.
2. The combination with a sewing machine and its support, of a gate comprising pivoted supports extending outwardly from the sewing machine and adapted to be 20 swung inwardly toward the same by pressure of the body thereon and to swing outwardly into normal position when pressure of the body thereon is released, means carried by said supports for guiding a strip 25 of fabric into said sewing machine, a guide 30 for the fabric interposed between said gate and the stitching mechanism of the sewing

machine, said guiding means on the gate moving upwardly and inwardly in relation to said latter guide when the gate swings inwardly toward the sewing machine.

35

3. The combination with a sewing machine and its support, of a gate comprising a pair of upper arms and a pair of lower arms mounted to swing and projecting from the sewing machine, upright supports 40 mounted on the outer ends of said pairs of arms and adapted to swing therewith toward the sewing machine, and fabric guiding means carried by said upright supports.

4. The combination with a sewing machine and its support, of a gate including upper and lower pivoted arms projecting from the sewing machine support, an upwardly extending supporting member pivoted to the outer end of said lower arm 50 and having a movable connection with the outer end of said upper arm, a fabric guiding member carried by said upwardly extending support and a link pivoted to the upwardly extending support at its place of 55 connection with said upper arm and connected to said lower arm between its ends for the purpose set forth.

Signed at the city of Newark, county of Essex and State of New Jersey this 24th day 60 of July, 1918.

JOHN BOSTON.
